UNITED STATES PATENT OFFICE.

JOSEPH DUKE, OF SEATTLE, WASHINGTON.

BEDSTEAD-JOINT.

1,122,265.

Specification of Letters Patent. Patented Dec. 29, 1914.

Application filed March 12, 1914. Serial No. 824,117.

To all whom it may concern:

Be it known that I, JOSEPH DUKE, a citizen of the United States, and a resident of Seattle, in the county of King and State of Washington, have invented a new and Improved Bedstead-Joint, of which the following is a full, clear, and exact description.

This invention relates to metal bedstead joints for connecting the side bars or spring frame with the posts of the head and foot pieces, the joint being of that type which includes a box bracket fastened to a corner post and to which a side bar or bed spring bottom frame is detachably interlocked.

The general objects of the invention are to improve and simplify the construction and operation of bedstead joints of the character referred to so as to be reliable and efficient in use, comparatively simple and inexpensive to manufacture and of durable and substantial design.

A further object of the invention is the provision of a novel form of box bracket made in two sections fitting in interlocking relation and having suitably arranged lugs to engage with a spring frame or a side bar of the bedstead.

Still another object of the invention is the provision of a novel form of corner construction for a spring frame, such construction having special reference to the corner post bracket with which it detachably interlocks.

With such objects in view, and others which will appear as the description proceeds, the invention comprises various novel features of construction and arrangement of parts which will be set forth with particularity in the following description and claims appended hereto.

In the accompanying drawing, which illustrates certain embodiments of the invention, and wherein similar characters of reference indicate corresponding parts in all the views, Figure 1 is a perspective view of a bedstead corner joint; Fig. 2 is a side view of Fig. 1; Fig. 3 is a perspective view of the box bracket removed; Fig. 4 is a similar view showing sections of the box bracket separate; Fig. 5 is a vertical sectional view on the line 5--5, Fig. 2; Fig. 6 is a horizontal section on the line 6--6, Fig. 5, with the spring frame removed; and Fig. 7 is a perspective view of a modified form of box bracket.

Referring to the drawing, 1 designates a

corner post of a foot or bed piece of a bedstead and which has fastened thereto a box bracket A that is adapted to interlock with one end of a side bar of a bedstead or with the corner construction B of the frame that holds the spring bottom for the bedstead. The box bracket is made in two sections *a* and *b* constructed as clearly shown in Fig. 4. The section *a* comprises top and bottom plates 2 and 3 disposed parallel, a side plate 4, and a curved end plate 5, the curvature of which corresponds to the curvature of the corner post 1. The top plate 2 has an upwardly-extending lug 6 adjacent the edge 7 which is opposite from the wall 4, and at the base of this lug 6 is a recess 8 in such edge 7. The bottom plate 3 has a small horizontally extending lug 9. At the upper and lower edges of the curved wall 5 are flanges 10 and 11 which are also curved to conform with the shape of the post 1. The section *b* of the box bracket comprises a side plate 12 and a curved end plate 13 which is shaped to conform to the end wall 5 of the section *a*, and this plate 13 fits between the flanges 10 and 11, as clearly shown in Fig. 3. A lug 14 extends upwardly from the side wall or plate 12 and cooperates with the lug 6 of the section *a* so as to form a single upstanding lug which interlocks with the side bar of the bedstead or equivalent part of its spring frame. A horizontally-extending lug or flange 15 projects from the bottom of the wall 12 and has a rectangular aperture 17, and adjacent one corner the wall 12 has an opening 18 which receives the lug 9 on the bottom 3 of the section *a*. The end plates 5 and 13 of the sections *a* and *b* have registering openings 19 through which extends a bolt 20, as shown in Fig. 6, such bolt having its head 21 disposed in the bed post 1 and projecting out of the same and into the box bracket A. By reason of the curvature of the end wall of the box bracket a single bolt is sufficient to hold the bracket firmly attached to the post without any tendency to turn on the bolt as an axis. It will be noted that the sections *a* and *b* have several interlocking portions. First, the lug 14 fits in the recess 8 and the lug 9 enters the opening 18, while the end wall 13 fits between the flanges 10 and 11 and also fits against the curved wall 5.

The side bar 22 of the bedstead is shown as of angle iron, and the upper flange 23

thereof has an opening 24 to receive the lug formed by the ears 6 and 14 of the two sections of the box bracket A. By this arrangement it is impossible for the two sections of the box bracket to be spread apart. The corner construction B includes a vertical plate or bracket 25 which is fastened by rivets or equivalent fastenings 26 against the outer face of the angle side bar 24, and this bracket 25, which is of any desired shape, has reinforcing or stiffening flanges 27 and 28 which are adapted to bear on the top of the side bar 22, and the lower end of the bracket 25 extends below the bottom edge 29 of the side bar so as to rest on the flange 15 of the box bracket A, and a tongue or lug 30 depends from the bottom edge 29 and enters the opening 17 in the flange 15. It will thus be seen that the side bar 22 is connected with the box bracket by the lug 6, 14 on the top of the latter, and the lug 30 carried by the side bar. The corner bracket 25 has fastened thereto a transverse angle bar 31 which has apertures 32 for receiving the springs or wires of a spring bed bottom. The bracket member 25 has a laterally-extending ear 33 at its upper part to which the angle bar 31 is fastened by a bolt or equivalent means 34.

In the modification shown in Fig. 7 the inner wall 4 of the box bracket A has means for fastening a cross bar 35 thereto, such means consisting of an opening 36 into which the bar extends. In forming the opening an ear 37 may be pressed out from the side of the box bracket and the cross bar 35 is preferably bolted thereto, as well as to the top of the box bracket, and for this purpose bolt-receiving openings 38 and 39 are provided.

From the foregoing description taken in connection with the accompanying drawings, the advantages of the construction and method of operation will be readily understood by those skilled in the art to which the invention appertains, and while I have described the device which I now consider to be the best embodiment thereof, I desire to have it understood that the device shown is merely illustrative, and that such changes may be made when desired as are within the scope of the appended claims.

Having thus described my invention, I claim as new and desire to secure by Letters Patent:

1. A bed post and a box bracket secured thereto, said bracket consisting of two sections and having upwardly extending ears forming a lug arranged to interlock with the side bar of the bedstead.
2. The combination of a bed post, with a box bracket fastened thereto, said bracket consisting of two interfitting sections, one section having a recess at one edge and an upwardly-extending ear at the recess, and

the other section having an ear arranged to enter the recess and register with the ear of the first section to form a single lug arranged to interlock with a bedstead side bar.

70

3. The combination of a bedstead corner post, with a box bracket comprising two sections having curved end walls fitting each other and shaped to fit the said post, and a fastener passing through the end walls 75 and post.

75

4. The combination of a bedstead corner post, with a box bracket comprising two sections having curved end walls fitting each other and shaped to fit the said post, a 80 fastener passing through the end walls and post, and flanges on one section at the end thereof and between which the end wall of the other section fits.

80

5. The combination of a bedstead corner 85 post, with a box bracket comprising two sections having curved end walls fitting each other and shaped to fit the said post, a fastener passing through the end walls 90 and post, flanges on one section at the end thereof and between which the end wall of the other section fits, and ears extending upwardly from the tops of the sections and arranged to form a single lug and adapted to interlock with a bedstead side 95 bar.

95

6. The combination of a bedstead corner post, with a box bracket comprising two sections having curved end walls fitting each other and shaped to fit the said post, a 100 fastener passing through the end walls and post, flanges on one section at the end thereof and between which the end wall of the other section fits, and ears extending upwardly from the tops of the sections and arranged to form a single lug and adapted to interlock with a bedstead side 105 bar.

105

7. A box bracket for bed posts comprising two detachably connected sections, a flange on one section and provided with a lug-receiving aperture, and a pair of ears 115 on the sections arranged to form together a single lug.

115

8. A box bracket for bed posts comprising a pair of interfitting sections, ears extending upwardly from the sections and arranged to form a single lug, and a flange 120 extending laterally from one section and having a lug-receiving aperture.

120

9. The combination of a bed post, a box bracket having an upwardly extending lug 125 and a laterally extending apertured flange, means concealed within the box bracket for connecting the same with the post, and a side bar having an aperture to receive the said lug and a lug to enter the aperture of the flange.

130

10. The combination of a bed post, a box bracket having an upwardly extending lug and a laterally extending apertured flange, means concealed within the box bracket for connecting the same with the post, a side bar having an aperture to receive said lug, and a bracket piece fastened to the said bar and having a depending lug to enter the aperture of the flange.
11. The combination of a bed post, a bracket thereon having at its lower portion an apertured flange and having at its upper portion a lug, a side bar having an aperture to receive the said lug, a bracket piece fastened to the side bar and having portions extending upwardly and downwardly from the side bar, a lug on the lower portion of the bracket piece to engage in the flange of the bracket, and a cross bar connected with the upper portion of the bracket piece and extending across the bracket.
12. The combination of a bracket, a side bar interlocking with the bracket, a bracket piece fastened to the side bar and interlocking with the bracket, said bracket piece having a portion extending upwardly above the side bar and provided with stiffening flanges resting on the side bar, and a cross bar connected with the bracket piece.
13. The combination of a bed post, a bracket thereon, an angular side bar having a vertical flange engaging the side of the bracket and a horizontal flange engaging the top of the bracket, interlocking means between the bracket and side bar, a bracket piece fastened to the outer surface of the
14. The combination of a bed post, a bracket thereon, an angular side bar having a vertical flange engaging the side of the bracket and a horizontal flange engaging the top of the bracket, interlocking means between the bracket and side bar, a bracket piece fastened to the outer surface of the side bar, said bracket piece extending downwardly below the side bar to interlock with the bracket, and a cross bar connected with the upper portion of the bracket piece at a point above the side bar.
15. The combination of a bed post, a bracket thereon, an angular side bar having a vertical flange engaging the side of the bracket and a horizontal flange engaging the top of the bracket, interlocking means between the bracket and side bar, a bracket piece fastened to the outer surface of the side bar, said bracket piece extending downwardly below the side bar to interlock with the bracket, said bracket piece extending upwardly above the side bar and having inwardly extending reinforcing flanges engaging the top of the side bar, and a cross bar connected with the upper extremity of the bracket piece.

In testimony whereof I have signed my name to this specification in the presence of two subscribing witnesses.

JOSEPH DUKE.
